United States Patent Office

Des. 189,856
Patented Mar. 7, 1961

189,856

FLOWER HOLDER

Austin J. Doran, 611 W. Arnold, Marshfield, Wis.

Filed June 13, 1960, Ser. No. 60,922

Term of patent 14 years

(Cl. D35—3)

Fig. 1 is a front perspective view taken from the right side and top of a flower holder embodying my new design, the bottom being substantially without significant ornamentation;

Fig. 2 is a rear elevational view thereof; and

Fig. 3 is a left side elevational view thereof.

I claim:

The ornamental design for a flower holder, substantially as shown and described.
